Primary Examiner — Jennifer Rivard*Assistant Examiner* — April Rivas(74) *Attorney, Agent, or Firm* — CBM Patent Consulting, LLC**CLAIM**

The ornamental design for a retractable tool box, as shown and described.

DESCRIPTION

FIG. 1 is a top view of a retractable tool box showing my new design;

FIG. 2 is a bottom view thereof;

FIG. 3 is a front view thereof;

FIG. 4 is a rear view thereof;

FIG. 5 is a left side elevational view thereof; and,

FIG. 6 is a right side elevational view thereof.

The broken line "Makita" logo illustrates portions of the retractable tool box and forms no part of the claimed design. The "Makita" logo is a registered trademark of the MAKITA CORPORATION OF Japan.
